A. W. CONNER,
KEY RING,
APPLICATION FILED MAY 10, 1920.

Patented Apr. 5, 1921.

A. W. Conner. INVENTOR.

BY

Jerry D. Kasey, ATTORNEY.

UNITED STATES PATENT OFFICE.

ALBERT W. CONNER, OF FALLS CITY, NEBRASKA.

KEY-RING.

Specification of Letters Patent.

Patented Apr. 5, 1921.

1,373,867.

Application filed May 10, 1920. Serial No. 380,281.

To all whom it may concern:

Be it known that I, ALBERT W. CONNER, a citizen of the United States, residing at Falls City, in the county of Richardson and State of Nebraska, have invented certain new and useful Improvements in Key-Rings, of which the following is a specification.

This invention relates to a key ring of that class in which the keys are held on a loop, the terminals of the loop being connected by a member which permits of the keys being removed from the loop.

A particular feature of the present invention resides in arranging a member closing the opening of the loop in such manner that it has permanent association with one terminus of the loop and releasable association with the other.

The invention has as another object the provision of a closure for the loop which connects the terminals of the loop in such manner that one end of the closure while permanently associated with its particular terminal of the loop is movable to locked and pivoted positions, the other end being releasable from its terminal only when the first mentioned end of the closure is moved to the pivotal position.

In the drawing:

Figure 1 is a perspective view of the key ring;

Fig. 2 is a side elevation with the loop closure in section;

Fig. 3 is a view similar to Fig. 2 but with the loop closure disengaged;

Fig. 4 is a perspective view of the parts of the key ring disassembled.

In detail:

The key ring, as shown in the accompanying drawing, comprises a U-shaped loop having the terminals 2 and 3 spaced apart as shown. The terminal end 2 consists of an enlarged portion having a keyhole slot 1 consisting of a round opening 4 and a narrow rectangular opening 5, the said keyhole slot being disposed with the round opening 4 toward the closed end of the loop.

The terminal 3 comprises a hook end 6 turned toward the closed end of the loop and the passage 7 of which is narrower than the width at the base of the hook.

The closure consists of the bar members 8 and 9, the former of which, at one end carries the lug 10 which is rounded on the

ends 11 as shown to have pivotal movement in the rounded opening 4 but is squared on opposite sides to enter the rectangular portion 5 of the keyhole slot so that when in 60 such position the bar 8 is keyed against pivotal movement with relation to the loop. The other end of the bar 8 carries a lug having a rounded or cylindrical portion as indicated at 12 and a rivet end 13, a rivet 65 end 14 being carried by the lug 10. In assembling the key ring the bar 8 is placed so that the lug 10 enters the rectangular portion 5 of the keyhole slot and the cylindrical portion 12 of the other lug enters 70 the base of the hook 6 as shown in Fig. 2, the bar 9 is then applied over the rivet ends 13 and 14 so that said rivet ends enter the holes 15 and 16 respectively and are riveted down as shown in Fig. 1.

With the closure thus assembled to the loop it is impossible to disengage the cylindrical member 12 from the hook 6, but if the lug 10 is moved so that it enters the round opening 4 of the keyhole slot it then 80 acts as a pivot for the closure and the arms of the loop will spring apart sufficiently to allow the closure to be rotated so that the cylindrical portion 12 may be disengaged from the hook 6 and keys applied to the 85 loop. After the closure has been moved to the open position as shown in Fig. 3 and the keys applied the closure is then rotated back with the cylindrical member 12 lying in the base of the hook 6 and the opposite 90 end having the lug 10 in the rectangular portion of the keyhole slot so that the closure is keyed against pivotal movement until again released by moving the keyed 95 end as previously described.

It is to be noted that the particular shape of the terminal 3 with its notched hook end permits a key with a small hole to be placed on the ring.

I claim:

1. A key ring comprising a spring loop, and a closure for the loop having selective pivotal and non-pivotal connection with one terminal of the loop and spring engagement with the other.

2. A key ring comprising a loop, a member connecting the terminals of the loop and having permanent selective pivotal and non-pivotal connection with one terminal and releasable engagement with the other 110 terminal.

3. A key ring comprising a loop, and a

- member connecting the terminals of said loop and having a permanent connection with one terminal of said loop, said connection being displaceable to locking and unlocking positions with respect to the terminal, the other terminal of said loop having means for releasable engagement with the free end of said connecting member when said connection is in an unlocking position.
10. 4. A key ring comprising a loop, a member connecting the terminals of the loop and having one end thereof movable to lock in a non-pivotal position, and the other end being releasable only when the first mentioned end is movable to pivotal position.
15. 5. A key ring comprising a loop, one terminal of the loop having a keyhole slot and the other terminal of the loop forming

a hook, and a member connecting the terminals and having a lug movable in the key-hole slot to prevent disengagement of the connecting member with the other terminal.

20. 6. A key ring comprising a loop, one terminal of the loop having a keyhole slot with the larger end of the slot disposed adjacent the closed end of the loop and the other terminal of the loop comprising a hook, a connecting member having a lug for pivotal engagement in the larger end of the keyhole slot and keyed engagement in the smaller end thereof, the other end of the connecting member having means for releasable engagement with the hook.

25. In testimony whereof I affix my signature.

ALBERT W. CONNER. [L. s.]
